[57] CLAIM

The ornamental design for a restaurant building, as shown and described.

DESCRIPTION

FIG. 1 is a front elevational view of a restaurant building showing my new design, the rear elevational view being the same;

FIG. 2 is a top plan view of the building;

FIG. 3 is an end elevational view of the building;

FIG. 4 is an end elevational view of an opposite end of the building from that shown in FIG. 3;

FIG. 5 is a front elevational view of an alternative embodiment of the building, which is the same as a rear elevational view of the building;

FIG. 6 is a top plan view of the building shown in FIG. 5;

FIG. 7 is an end elevational view of the building shown in FIG. 5; and

FIG. 8 is an elevational view of an opposite end of the building from that shown in FIG. 7.

Fig. 1.Fig. 2.Fig. 3.Fig. 4.Fig. 5.Fig. 6.Fig. 7.Fig. 8.
